TELEPHONE ATTACHMENT

Charles Kolodny, Baltimore, Md.

Application July 8, 1941, Serial No. 401,517

10 Claims. (Cl. 179—185)

My invention relates to new and useful improvements in telephone attachments, and more particularly to a sanitary device therefor, the primary object being to provide an attachment which may be applied readily to the mouth-piece or transmitter of either the wall type or French type telephones to insure cleanliness and avoid transmission of germs.

Various devices have been suggested from time to time for the purpose of presenting a sanitary mouth-piece for telephones, but due to the complicated construction thereof, cost of manufacture and possible interference with telephone communications, the same have not been adopted. My invention contemplates a simple and durable device which may be quickly and readily applied or removed, one which is simple and inexpensive to manufacture and which will not in any sense whatsoever interfere with or conflict with transmission of messages.

A further object of the invention resides in the provision of a device carrying a roll of sanitary paper capable of being drawn across the transmitter at will and torn, and then destroyed.

A still further object resides in the provision of a flexible element removably attached to the paper support and adapted to be resiliently and removably engaged with the mouth-piece or transmitter of the telephone.

A further object of the invention resides in constructing a support for the roll of paper which will enable the latter to be readily drawn across a plane forward of the transmitter and torn from the support without effort.

A still further object resides in providing a device of the character described which is simple and durable in construction, inexpensive to manufacture and one which will be very efficient in use.

With these and numerous other objects in view my invention consists in the novel features of construction, combination and arrangement of parts as will be hereinafter referred to and more particularly pointed out in the specification and claims.

In the accompanying drawing, forming a part of this application,

Figure 1 is a side elevation of a telephone of the French type showing my sanitary attachment in place thereon;

Figure 2 is a plan view thereof;

Figure 3 is a side elevation of the receiver shown on an enlarged scale with my improved attachment applied to the transmitter;

Figure 4 is a transverse vertical section taken

on the line 4—4 of Figure 5, with parts in elevation;

Figure 5 is a central vertical longitudinal section taken on the line 5—5 of Figure 4, with the receiver shown in elevation;

Figure 6 is a front face view of the attachment removed, and

Figure 7 is a rear face view thereof.

In describing the invention, I shall refer to the drawing in which similar reference characters designate corresponding parts throughout the several views, and in which the numeral 1 designates a telephone instrument of the French type, wherein the receiver 2 thereof has the ear piece 3 at one end and the mouth-piece or transmitter 4 at the opposite end. While I have shown my attachment as applied and particularly applicable to the mouth-piece of this type of telephone instrument, it will be understood, of course, that it may be applied to transmitters or mouth-pieces of other types of phone instruments.

Carriers of various diseases transmit the germs through the mouth and it has been discovered that telephone instruments aid and abet in the transmission of such germs. It is the purpose of my invention to provide a device, simple in construction, and inexpensive to maintain, which may be readily attached to the mouth-piece to present at all times a clean and sanitary locality on the telephone, against which or adjacent to which the mouth of the speaker may be placed.

My attachment generally comprises a support 5 of plate-like formation carrying a roll 6 of sanitary paper or the like, and a removable or detachable means 7 for resiliently and removably engaging the support with the mouth-piece of the telephone. The plate 5 has one end thereof formed into a partial housing, the latter being designated by the numeral 8. This is accomplished by forming at one end of the plate an upstanding wall 9 and side walls 10. Applied thereover is a top member 11 having side walls 12 and a front wall 13. This housing supports a shaft 14 on which the roll of paper 6 is mounted, as clearly shown in Figure 5 of the drawing. As seen in Figures 6 and 7, the shaft 14 has an angular end and a pin passing through the opposite end so as to retain the same in place, but obviously the pin may be readily removed and a new roll of paper inserted when necessary.

The paper from the roll 6, as clearly shown in Figures 5 and 6 of the drawing, is guided through a slot 15 in the bottom of the housing 8 and extends over the front face of the plate 5, being guided in position thereover by the bent

ears 16 formed integral with the side edges of said plate 5. After extending for the greater length of the plate 5, the paper is guided through a second slot 17 formed transversely of the plate adjacent the end thereof opposite that supporting the housing 8, and the paper is adapted to extend to a point beyond the free edge 18 of the plate or support 5. That portion of the plate between the free edge 18 and the slot 17 is depressed from the front face thereof as shown at 19 to provide hemispherical projection on the rear face of the plate. These projections have a tendency to force the free end of the web of paper extended through the slot 17 away from the plate 5, as clearly shown in Figure 5, so that the paper may be drawn across the plate from the roll without effort.

The central portion of the plate 5 is perforated, as shown at 20, so that no serious obstruction occurs at the point where the voice passes to the transmitter. The plate is also struck-up from a plurality of positions surrounding the perforations 20 to form the angular bent ears 21. These ears constitute engaging and supporting means for the transmitter engaging means 7.

The transmitter engaging means 7 may be of any desired shape but is preferably hemispherical and formed of rubber, synthetic rubber, metal or plastic resilient material. I do not wish to be limited as to the character of material to be used in constructing this means, although I have found rubber to be cheap and effective. An opening is formed at the end of this hemispherical member 7 whereby the same may be resiliently snapped in place on the angularly bent ears 21 of the plate 5. This member 7 may be readily and snugly engaged with the mouth-piece or transmitter 4 of the telephone, and in order to aid and assist in the retention of this means on the mouth-piece, the curved arms 22 may be provided on the member 7 by integral or other connection. Thus the transmitter engaging means may be readily applied, with the plate thereon so that the paper from the roll 6 will cover the front of the transmitter. This paper may be drawn from the roll at will, torn off and destroyed, so that each user of the instrument will have a clean and sanitary location adjacent to which his mouth may be placed. If desired, the paper may be used also as a memorandum sheet, and that portion of the plate 5 between the slot 15 and the ears 21 may be used as a backer or support for the paper when writing thereon.

From the foregoing description of the construction of my improved invention, it will be seen that I have provided a simple, inexpensive and efficient means for carrying out the various objects of the invention.

While I have particularly described the elements best adapted to perform the functions set forth, it is obvious that various changes in form, proportion and in the minor details of construction may be resorted to, without departing from the spirit or sacrificing any of the principles of the invention.

Having thus described my invention, what I claim is:

1. In a sanitary attachment for telephones, a supporting plate, a casing for a roll of paper at one end of said plate having a removable section constituting a closure therefor, means to guide the web of paper across said plate, raised means on said plate to prevent the paper from adhering

to said plate, and a substantially hemispherical elastic member detachably mounted on the rear face of said plate and being of dimensions adapted to fit snugly about and frictionally grip the mouth-piece of a telephone.

5. In a sanitary attachment for telephones, a supporting plate carrying a sanitary element and having a perforated area covered by the sanitary element, a substantially hemispherical flexible member adapted to fit about and having frictional gripping engagement with the mouth-piece of a telephone, and means for detachably securing said flexible member to the rear face of said supporting plate in encircling relation to the perforated area thereof.

10. In a sanitary attachment for telephones, a supporting plate carrying a sanitary element, ears cut from the plate and projecting from the rear face of said plate about a perforated area 20 of the plate, and a substantially hemispherical flexible member having an opening therein, the ears of said plate passing through the opening and gripping walls of the said member about margins of the opening, said hemispherical member being adapted for frictional and encircling engagement with the mouth-piece of a telephone.

15. In a sanitary attachment for telephones, a supporting plate carrying a sanitary element, and a substantially hemispherical elastic member detachably engaged with and extending rearwardly from the rear face of said plate about a perforated area thereof and adapted for encircling and frictional engagement with the mouth-piece of a telephone to removably mount 30 the plate across a telephone receiver with the perforated area of the plate in front of the receiver.

20. In a sanitary attachment for telephones, a supporting plate, a sanitary element carried thereon comprising a roll of paper having the web thereof guided over the front face of said plate, raised means on said plate to prevent the web of paper from adhering to the latter, and a substantially hemispherical rubber member 45 detachably engaged with the rear face of the plate, said rubber member being of dimensions adapting same to enclose and elastically grip the mouth-piece of a telephone.

25. In a sanitary attachment for telephones, a supporting plate carrying a sanitary element, ears formed on the rear face of said plate and extending downwardly therefrom in spaced relation to each other about an area intermediate the length and width of the plate, and a substantially cup-like member formed of elastic material and having an enlarged central opening therein, the cup-shaped member being snapped into place about the ears of said plate to detachably hold the said member in engagement with the plate, said cup-like member having yieldable jaws for frictional encircling engagement with the mouth-piece of a telephone.

30. In a sanitary attachment for telephones, a supporting plate having transverse slots there-in adjacent opposite ends thereof, a roll of paper supported at one end of said plate having the web thereof guided through said slots so that the paper extends over the outer face of the plate between the slots, means for guiding the paper as it is drawn across the plate, bosses spaced from each other transversely thereof and extending downwardly therefrom adjacent the end of the plate opposite that supporting the roll of paper and constituting means to direct the paper away from the under face of the plate and

enable same to be readily grasped, and means for supporting the plate on the mouth-piece of a telephone.

8. In a sanitary attachment for telephones, a supporting plate having transverse slots therein adjacent opposite ends thereof, a roll of paper supported at one end of said plate having the web thereof guided through said slots so that the paper extends over the outer face of the plate between the slots, means for guiding the paper as it is drawn across the plate between the slots, projections formed on the under face of the plate between the end thereof opposite that supporting said roll of paper and the adjacent slot, whereby to direct the end of the web away from the under face of the plate to enable ready grasping thereof, and means for detachably supporting the plate on the mouth-piece of a telephone.

9. In a sanitary attachment for telephones, a supporting plate, means carried by said plate for holding a supply of paper, means to guide the paper across said plate, said plate being provided with raised portions to prevent the free end of the paper from adhering to the plate, and means for detachably mounting said plate against the front end of a telephone transmitter comprising a shell of elastic material having the form of a substantially truncated hemisphere

5 and open at its front and rear ends, said shell being of a depth and diameter adapting it to fit about a telephone transmitter in frictional gripping engagement therewith for the entire circumference of said transmitter, and tongues extending rearwardly from the open rear end of said shell in spaced relation to each other circumferentially thereof for gripping the telephone transmitter therebetween and assisting in holding the shell in engagement with the transmitter.

10. In a sanitary attachment for telephones, a supporting plate, a roll of paper mounted at one end of said plate, means to guide the web of paper across said plate, said plate being provided with raised portions to prevent the free end of the paper from adhering to the plate, and means for detachably holding said plate against the front end of a telephone transmitter in covering relation thereto comprising a shell of elastic rubber having the form of a substantially truncated hemisphere open at its front and rear ends and having its open front end detachably mounted against the rear face of said plate, said shell being of a depth and diameter adapting it to fit snugly about a telephone transmitter in frictional gripping engagement therewith for the entire circumference of the transmitter.

CHARLES KOLODNY.
